A. POLLAK

LEAD PENCIL

Original Filed Feb. 9, 1922

Inventor:

ABRAHAM POLLAK.

By his Attorney,

morney.
Charles C. Gill.

UNITED STATES PATENT OFFICE.

ABRAHAM POLLAK, OF NEW YORK, N. Y., ASSIGNOR TO SAMUEL KANNER, OF NEW YORK, N. Y.

LEAD PENCIL.

Original application filed February 9, 1922, Serial No. 535,273. Divided and this application filed January 2, 1923. Serial No. 610,092.

To all whom it may concern:

Be it known that I, ABRAHAM POLLAK, a citizen of the United States, and a resident of New York city, in the county of New York and State of New York, have invented certain new and useful Improvements in Lead Pencils, of which the following is a specification.

The invention relates to improvements in mechanical lead pencils, and it consists in the novel features, structure and combinations of parts hereinafter described, and particularly pointed out in the claims.

This application is a division of my application filed February 9, 1922, Serial No. 535,273.

My invention pertains more particularly to a lead pencil containing a chamber for reserve leads and having means for propelling its lead forwardly for writing purposes, the chamber being of rotary tube character and its outer end being normally closed by a plug rubber eraser, and my invention resides in a novel slidable cap or head applied to the outer end of the pencil normally concealing the rubber eraser and adapted when pulled outwardly to be turned laterally for exposing said eraser, said cap or head having a slidable and also a pivotal connection by means of side arms with said rotary tube and serving as means for rotating said tube for propelling the writing lead, and said side arms in the normal condition of the pencil being concealed between said rotary tube and the exterior casing of the pencil, so that only the cap or head proper, which is of ornamental character, is exposed.

The invention will be fully understood from the detailed description hereinafter presented, reference being had to the accompanying drawings, in which:

Fig. 1 is a longitudinal section through a lead pencil equipped with features constituting the present invention;

Fig. 2 is a side elevation, partly in section, of the outer end portion of the pencil and illustrates the closing cap as having been drawn outwardly to the full extent permitted by its pivotal arms preparatory to the cap being turned laterally to expose the rubber eraser carried by the interior rotary tubular member of the pencil, said tubular

member affording a chamber for reserve leads;

Fig. 3 is a side elevation of the outer end portion of the pencil and illustrates the cap of Fig. 2 as having been turned downwardly to expose the rubber eraser;

Fig. 4 is a vertical section through the pencil taken on the dotted line 4—4 of Fig. 1, and

Figs. 5, 6 and 7 show the respective parts of the lead-holding and actuating mechanism finally disposed centrally within the pencil.

The pencil presented herein is the pencil shown in my aforesaid application and the subject matter of this application resides in the cap or head construction at the outer end of the pencil, such subject matter being a separate invention from the other portions of the pencil claimed in said application and not necessarily limited thereto or confined to use therewith.

The general features of the pencil will therefore be briefly referred to and the construction made the subject hereof will be specifically described.

The pencil comprises four main tubular members 10, 11, 12 and 13, the member 13 being polygonal in cross-section and rigid with the member 11 and carried thereby.

The member 10 constitutes the exterior shell or casing of the pencil and has a forward tip-member 14 for the forward end of the lead 15.

The rear end of the casing member 10 is normally closed by a cap 16 whose details will be hereinafter described and which, by means of a yoke 17, is pivoted to the tubular member 12, said member 12 having slots or elongated openings 18 in its opposite sides to receive the forwardly bent ends 19 of the side arms 119 of said yoke and permit said yoke with the cap 16, to have a longitudinal movement when pressed toward the rear end of the casing 10 or to the position shown in Fig. 1 or drawn outwardly therefrom, as shown in Fig. 2, preparatory to being swung downwardly to the position shown in Fig. 3 to expose the eraser 20 which plugs the rear end of the tubular member 12.

The tubular member 12 is a plain cylindrical barrel having the openings 18 near

its rear end and at its front end being secured in an annular recess 21 formed on the rear end of a nut 22 which contains a spirally threaded hole 23 in line with the 5 longitudinal center of the tube 12 and a hollow central portion 24 constituting a recess to freely receive the rear end of the tubular member 13, as shown in Fig. 1. The nut 22 has rounded forward edges 25 and an 10 annular rounded groove 26. The threaded hole 23 in the nut 22 cooperates with the longitudinally movable spiral rod 27, as hereinafter described, and the forward end of the nut 22 enters and interlocks with the 15 rear end of the tubular member 11, said member 11 at its rear end being slit to form spring members adapted to pass upon the nut 22 and then spring inwardly into the recess 26 thereof. In the assembly of the parts 20 the nut may be forced into the rear end of the tubular member 11 and when therein said nut serves to connect the tubular members 11, 12 together and permit the member 12 to have free rotary movement and to rotate 25 said nut, while the member 11 remains stationary with the outer casing 10.

The tubular member 12 is therefore rotatable within the outer shell or casing 10 and carries the nut 22, cap 16 and eraser 20, and 30 said member 12 forms within it a chamber for reserve leads, said chamber being accessible when the eraser 20 is withdrawn from the tube and closed when said eraser is returned to position.

35 The tubular member 11 is, at its forward portion, of reduced diameter, being offset inwardly, as at 129, and continued forwardly, as at 30, and said portion 30 forming a concentric tube which projects into the tip 14 of the casing 10. The offset portion 129 of the tube 11 engages the rear end of the tapered portion or tip 14 of the casing 10, and the tube 11 has a firm friction-fit within the casing 10.

40 The tubular member 13 is concentrically within the tube 11 and its member 30, and at its rear end said tube 13 freely enters the recess 24 of the nut 22, while at its forward portion said tube 13 fits closely within the 45 auxiliary tube 30 and projects forwardly beyond the same and is turned inwardly at its forward extremity to form an annular flange 31. The tubular member 13 is polygonal in cross-section and rigidly held within the auxiliary portion 30 of the tube 11, whereby the tubular members 11, 13 become a unit and are stationary within the outer casing 10.

45 The operative mechanism occupying a central longitudinal position within the pencil and by means of which the lead is propelled forwardly or retracted rearwardly on the rotation in one direction or the other of the tube 12, is shown detached in Figs. 5, 6 and 7 and consists of a spirally threaded

rod or screw 27 having on its forward end a polygonal head 33 containing a threaded recess 34, a propeller rod 35 threaded on its rear end to be screwed into said recess 34 and having on its forward end a head or 70 section 36 of somewhat greater diameter than the body of the rod 35, a coiled spring 37 confined on the rod 35, and a tubular lead-clutch or member 38 having a polygonal head 39 and slit sides 40 to grasp the 75 lead 15. The head 39 has a hole 41 in it, and in the assembly of the parts the rod 35 is, starting at its rear end, inserted into the clutch member 38 from the forward end thereof and through the hole 41, and then the spring 37 is placed upon the rod 35 and compressed to some extent thereon, whereupon the threaded rear end of the rod 35 is screwed into the recess 34 of the head 33 on the rod or screw 27, the spring 37 then being 80 confined between said head 39 and said head 33. The head 36 on the rod 35 is adapted to have longitudinal movement within the clutch member 38 and at its forward end engages the lead 15. 85

The polygonal head 33 on the rod or screw 27 and the polygonal head 39 on the clutch member 38 conform to the interior cross-section of the polygonal tube 13, and the forward edge of the head 39 90 is normally pressed against the stop flange 31 on the end of said tube 13 by the spring 37. The heads 33, 39 are prevented from rotating within the tube 13 by reason of the polygonal cross-section of said heads 100 and tube, and hence the screw or rod 27, rod 35 and clutch member 38 can have no rotary motion. The heads 33, 39 may, however, have longitudinal sliding movement within the tube 13. The means for propelling the heads 33, 39 and with them the rod 35 and clutch member 38, forwardly to expose or wholly eject the lead 15 and for retracting said heads, rod and clutch member to withdraw the lead into the pencil, 105 consist of the rotary tube 12, nut 22 and rod or screw 27, said rod or screw moving forwardly when the said tube and nut are turned in one direction and rearwardly 110 when said tube and nut are turned or rotated in the reverse direction. The clutch member 38, rod 35 and screw 27 move forward with substantial uniformity until the head 39 meets the stop flange 31, and during this movement the head 36 on the rod 35 exerts a yielding pressure on the lead due to the presence of the spring 37. After a lead has become unduly short and it is desired to expel the same from the pencil, the tube 12 and nut 22 are turned to propel the rod 35 and clutch member 38 forwardly until the head 39 reaches the stop flange 31 on the tube member 13 and are then further turned in the same direction to 115 propel the rod 35 and its head 36 along 120 125 130

through the clutch member 38 and against the piece of lead 15 until said piece has been expelled.

The rotation of the tubular member 12 and nut 22 to cause the traveling movement of the rod or screw 27 and its connected parts, is effected by holding the main casing 10 stationary and turning, with the thumb and finger, the cap 16 when said cap is in its operative position at the rear end of said casing, as shown in Fig. 1.

The cap 16 and yoke 17 are of special construction and arrangement. The yoke 17 consists of two side arms 119 whose forward ends 19 freely enter the slots 18 of the tube 12 and a disk head 50 which connects the rear ends of said arms and is confined within the cap 16. The cap 16 has an enlarged outer end affording an ornamental finish for the pencil, an ornamental bead 51 at its inner edge to engage the rear edge of the main casing 10 and plain sides 52 having indented lugs 53 which perform two functions, one being to prevent the escape of the cap from the yoke 17, while at the same time permitting the cap to be slid inwardly on said yoke and the rear end of the tube 12 to the position shown in Fig. 1 and outwardly from said tube 12 and partly from off the yoke 17 to the position shown in Fig. 2, after which the cap and yoke may be turned downwardly, as shown in Fig. 3, clear of the eraser 20. The cap 16 provides a chamber for the outer portion of the eraser 20, and when the cap and yoke are turned to a horizontal position while extended in the direction from each other (Fig. 2), the cap may be pushed forwardly on the yoke 17 and tube 12 and will push the yoke forwardly until the bent end portions 19 of the yoke slide to the forward ends of the slots 18 and pass below the outer edges of the main casing 10, the whole then taking the position shown in Fig. 1. When the cap 16 is in the position shown in Fig. 1, it will be utilized as a key for rotating the tube 12, and at this time the indented lugs 53 will perform their second function, to-wit, that of engaging the arms 119 and through said arms imparting to rotary movement of said cap to the tube 12 for actuating the screw 27 and parts associated therewith, said lugs 53 engaging diagonally opposite edges of said arms when the cap 16 is turned clockwise and the other diagonally opposite edges of said arms when the cap is turned counter-clockwise. The cap 16 and yoke 17 thus serve as means for turning the tube 12 in either direction and the cap 16 serves as a finish for the rear end of the pencil and also affords a chamber concealing the eraser 20. The cap 16 is pulled outwardly and then downwardly (Fig. 3) when the eraser 20 is to be used or when the eraser

is to be detached for exploding the reverse-lead chamber in the tube 12.

When the screw 27, rod 35, spring 37 and clutch member 38 have been assembled as described, the screw 27 may be screwed into and through the nut 22 to the requisite extent and thereupon the clutch member 38, rod 35, spring 37, head 33 and forward end of the screw 27 will be moved forwardly into the hexagonal or polygonal tube 13 and the forward end of the nut 22 will be forced into the rear end of the tube 11, thus assembling all the interior parts of the pencil quickly and into unit form. The exterior casing 10 will then be pushed in a rearward direction over said assembled interior parts, and finally the eraser 20 will be applied and the cap 16 and yoke 17 will be turned upwardly and then pushed forwardly on the tube 12 and to their operative position shown in Fig. 1.

What I claim as my invention and desire to secure by Letters Patent, is:—

1. A mechanical lead pencil comprising an exterior casing containing a rear rotary tube from which the lead propelling mechanism is operable, said tube affording a chamber closed at its rear end by a plug, and means for manually rotating said tube comprising a hollow head and a yoke connected therewith and pivotally connected with said tube, said head being slidable on said yoke and adapted to be drawn outwardly thereon and then turned downwardly therewith to expose the plug. 100

2. A mechanical lead pencil comprising an exterior casing containing a rear rotary tube projecting at its rear end beyond said casing and affording a lead holding chamber closed at its rear end by a plug and from which tube the lead propelling mechanism is operable, and means for manually rotating said tube comprising a hollow head adapted to fit upon said tube and pass into abutting relation to the end of said casing and a yoke comprising connected side-arms pivoted to said tube and on which said head is slidably mounted so as to be drawn rearwardly from off said tube and turned downwardly with said arms. 110

3. A mechanical lead pencil comprising an exterior casing containing a rear rotary tube projecting at its rear end beyond said casing and affording a lead holding chamber closed at its rear end by a plug and from which tube the lead propelling mechanism is operable, and means for manually rotating said tube comprising a hollow head adapted to fit upon said tube and pass into abutting relation to the end of said casing and a yoke comprising connected side-arms pivoted to said tube and on which said head is slidably mounted so as to be drawn rearwardly from off said tube and turned downwardly with said arms, said head being 120

equipped at opposite sides with inwardly projecting lugs to engage said arms at diagonally opposite edges thereof when said head is rotated for imparting rotary motion to said tube.

4. A mechanical lead pencil comprising an exterior casing containing a rear rotary tube projecting at its rear end beyond said casing and affording a lead holding chamber closed at its rear end by a plug and from which tube the lead propelling mechanism is operable, and means for manually rotating said tube comprising a hollow head adapted to fit upon said tube and pass into abutting relation to the end of said casing and a yoke comprising connected side-arms pivoted to said tube and on which said head is slidably mounted so as to be drawn rearwardly from off said tube and turned downwardly with said arms, the means securing said side arms to said tube being elongated openings in said tube and extending outwardly from below the end of said casing and inwardly extended forward ends on said arms projected through said openings and slidably longitudinally therein, whereby when said head and arms are pressed forwardly to closed position, the forward portions of said arms pass within said outer casing and have a snug engagement therewith.

5. A mechanical lead pencil comprising an exterior casing containing a rear rotary tube projecting at its rear end beyond said casing and affording a lead holding chamber closed at its rear end by a plug and from which tube the lead propelling mechanism is operable, and means for manually rotating said tube comprising a hollow head adapted to fit upon said tube and means associated with said head and pivotally connected with said tube and adapted to communicate the rotary motion of said head to said tube and also to permit said head to be slid outwardly from said tube and

turned downwardly, said head being adapted to pass into abutting relation to said casing and conceal said rotary tube and also the means connecting the head therewith.

6. A mechanical lead pencil comprising an exterior casing, a rear rotary tube therein projecting rearwardly beyond said casing and from which the lead propelling mechanism is actuated, a plug closing the outer end of said tube, and means for manually rotating said tube comprising a hollow head adapted to fit upon and conceal the projecting end of said tube and pass into abutting relation to the end of said casing, a yoke having connected side arms extending from within said head and pivotally connected with said tube and upon which said head is slidable and means for imparting rotary motion of said head to said arms and therethrough to said tube, said arms in the normal condition of the pencil being concealed.

7. A mechanical lead pencil comprising an exterior casing, a rear tube therein and spaced therefrom and projecting rearwardly beyond said casing, a plug closing the outer end of said tube, a hollow head fitting upon and concealing the projecting end of said tube and engaging the end of said casing and yoke arms connecting said head with said tube, said tube being slotted to pivotally receive the inner ends of said arms and permit sliding movement of the arms when said head is drawn rearwardly off from and returned to said tube, said head being slidable on said arms and the said arms in the normal condition of the pencil being concealed in part within said head and in part within the space between said casing and said tube.

Signed at New York city, in the county of New York and State of New York, this 11th day of December A. D. 1922.

ABRAHAM POLLAK.
